UNITED STATES PATENT OFFICE.

GEORGE G. HINSDALE, OF SOMERVILLE, MASSACHUSETTS.

YIELDING UNIT.

1,120,714.

Specification of Letters Patent.

Patented Dec. 15, 1914.

Application filed December 9, 1912. Serial No. 735,853.

To all whom it may concern:

Be it known that I, GEORGE G. HINSDALE, of Somerville, in the county of Middlesex and State of Massachusetts, have invented 5 certain new and useful Improvements in Yielding Units, of which the following is a specification.

This invention relates to improvements in yielding units of that class which is more 10 especially adapted for use in connecting two bodies so that they will normally be held a given distance apart but may be made to approach or recede from each other by and against the yielding action of said units.

15 The invention is carried out substantially as illustrated on the accompanying drawing which forms an essential part of this specification and whereon like characters of reference refer to like parts wherever they occur 20 thereon.

On the drawings, Figure 1 represents a side elevation of the yielding unit in its normal position. Fig. 2 represents a similar side elevation of the unit showing parts 25 thereof in longitudinal section, and showing the unit in its extreme expanded position as occupied when two bodies connected by said unit have been moved apart to the extreme limit of their movement in that 30 direction. Fig. 3 represents a similar view to that shown in Fig. 2 but seen from a position at right angles to that of Fig. 2 and showing the parts of the unit in their extreme contracted positions as occupied when 35

two bodies connected by said unit have been moved toward each other to the extreme limit of their movement in that direction. Fig. 4 represents a cross section of the unit 40 on the line $x-x$ in Fig. 3, showing the means whereby the several parts of the unit are securely held assembled without the use 45 of screwed, welded or riveted joints of any kind and whereby they can be easily taken apart when desired. Fig. 5 represents a detail end view of one of the bearing members which engage and support the yielding medium used in the unit. Fig. 6 represents a side elevation of one of the sliding arms used in the unit. Fig. 7 represents a side 50 elevation of the other sliding arm used in the unit. Fig. 8 represents a detail side elevation of one of the locking pieces which form the means whereby the parts of the unit are held assembled.

55 In forming a yielding unit of this class, when the yielding medium used consists of

a metal spring, it is essential that the metal of the spring should always be stressed in the same way independent of the movements of the bodies connected by said unit, whether 60 they are moved apart or toward each other. It is also desirable that the various members or parts entering into the construction of the yielding unit should be made as simple and inexpensive to manufacture as possible; 65 that the various parts of the unit be so made as to be assembled and the unit held together without the use of screws, bolts, nuts, or other screwed connections of any kind, or brazed, welded or riveted joints, and 70 without bending, twisting or otherwise changing the shape of any of the constituent parts of the unit during the process of assembling the unit, thereby obtaining a device free from all joints liable to become 75 loose or separated in use and one in which the several parts of the unit may be easily and quickly separated without destroying or injuring any of its parts.

In the device forming the subject matter 80 of this invention, I obtain all of the foregoing useful, important and desirable results and with the additional result that ample and uniform strength is secured in all parts of the unit. It will also be seen 85 by the complete description of the invention that the action of all parts is direct and thus free from friction due to the eccentric application of stresses.

The invention as herein described and 90 shown is designed more especially with reference to its use as a yielding unit in a resilient wheel but it will be evident that it may be equally as well applied when a yielding unit of this nature is desired for other articles, devices or the like. 95

As shown on the drawings, the yielding medium 1 consists of an open coil helical spring. This spring is supported and engaged by two bearing members 2 and 2' one 100 at each end thereof, which bearing members are provided with the respective thimble-like projections 3 and 3' extending from one bearing member toward the other bearing member and located within the coil of the 105 spring, thus forming a support for the spring and keeping its coils in proper alignment.

Sliding arms 4 and 4' are located within the coil of the spring 1 and the thimble-like 110 projections 3 and 3' of the bearing members 2 and 2' and project outside said bearing

members where they are provided with any desired means for attaching the unit to the bodies to be connected thereby. On the drawings I have shown the arms provided 5 with the respective common male pivotal connection 5 and the female pivotal connection 5' whereby several units may be connected into a continuous series, as in a resilient wheel or similar structure. The sliding 10 arms are provided with the respective shoulders 6 and 6' adjacent to the outer ends of the arms, and at their inner ends with the respective shoulders 7 and 7' substantially as shown. Locking pieces, preferably made 15 in two parts 8 and 8' and shown as semi-circular disks so as to allow them to embrace the sliding arms between the shoulders thereon, fit within the respective projections 3 and 3' on the bearing members 2 and 2'. The inner ends of the projections 3 and 20 3' are provided with the respective perforations 9 and 9' so shaped as to permit the ends of the arms to be inserted through the same but not to permit the locking pieces 25 to pass through, which locking pieces bridge the respective perforations 9 and 9' thus forming a bearing for the shoulders 6 and 6' and 7 and 7' and holding the several parts of the unit assembled.

30 To permit the locking pieces to be placed in their proper position when assembling the parts of the unit, the spring is compressed, and the inner ends of the projections 3 and 3' are brought together as shown 35 in Fig. 3. This positioning of the parts leaves sufficient space between the outer face of the bearing members 2 and 2' and the respective shoulders 7'-6 and 6'-7 to permit the locking pieces to be inserted in their 40 proper positions.

It is intended that the yielding medium shall be placed in position under slight stress, that is with a small amount of initial compression. Thus the locking pieces are 45 always securely held in their proper places as the shoulders on the sliding arms are always in contact with them, or the locking pieces may be made a force fit and be driven into the thimble-like projections as desired.

50 The operation of the unit when in use is such that the shoulders 7 and 7' will engage the locking pieces 8 and 8' when the two bodies connected by the yielding unit are moved apart causing the sliding arms to 55 move outward and this engagement between said shoulders and the locking pieces will cause the compression of the spring or other yielding medium used in the unit, but when the bodies connected by the unit are moved 60 toward each other causing the sliding arms to move inward, the shoulders 6 and 6' will engage the locking pieces 8 and 8' and will also cause a compression of the yielding medium. Thus the yielding medium is 65 always compressed independent of the direc-

tion in which the connected bodies and consequently the sliding arms are moved.

By the construction of the unit as herein described all joints and connections that might loosen or come apart are eliminated 70 and by the use of the thimble-like projections on the bearing members a wide range of resilient action within a very limited space is obtained, and this is a very important result when the unit is to be used 75 within a resilient wheel or similar construction where the available space is naturally very limited.

Having thus fully described the nature, construction and the operation of this invention, I wish to claim as follows:

1. An elastic connecting device comprising spaced open-ended bearing members, an elastic element supported thereby, a plurality of arms extending through the open-ended bearing members and slidably longitudinally with relation to each other and each arm provided with spaced shoulders, and locking pieces arranged between said shoulders and the outer ends of the open-ended bearing members whereby the movement of the arms in either direction causes the elastic element to be compressed.

2. An elastic connecting device comprising spaced oppositely disposed bearing members, each including a projection extending toward the projection on the other bearing member, each bearing member being open-ended with the bores of the bearing members arranged in alinement, a plurality of oppositely disposed sliding arms each having two spaced shoulders thereon, said arms passing through the bores of the bearing members and through the said projecting portions thereof, a locking device 100 introduced between the outer surface of each projection of each bearing member and the adjacent surfaces of the shoulders on the arms, and an elastic element arranged between the bearing members and embracing the said projections thereon and the sliding arms.

3. An elastic connecting device comprising an elastic element, bearing members at opposite ends of the elastic element each bearing member having a thimble-like projection embraced by the elastic element, the bearing members including their thimble-like projections being open-ended, arms passing through the bearing members and the thimble like projections thereof and slidably longitudinally relative to each other, each arm having a shoulder disposed normally adjacent the outer end of the corresponding bearing member, and locking pieces inserted between said shoulders and the bearing members.

4. An elastic connecting device comprising an elastic element, a bearing member at each end of the elastic element to support

- the latter, each bearing member including a thimble-like projection extending into the elastic element, the bearing members and their projections being open-ended and arranged in alinement, arms slidable longitudinally relative to each other in said bearing members and their said projections and extending beyond the outer ends of the bearing members, each arm having a shoulder thereon arranged normally outside of the respective bearing member, and a sectional locking device embracing sliding arms and arranged within the thimble-like projections of the bearing members.
5. An elastic connecting device comprising an elastic element, a bearing member arranged at each end of the elastic element, each bearing member including a thimble-like projection which extends into the corresponding end of the elastic element, the bearing members and their thimble-like projections being open-ended and arranged in alinement, arms projecting into said bearing members and their said projections and slidably longitudinally relative to each other and extending beyond the outer ends of the bearing members, the arms each having a shoulder outside the outer end of the corresponding bearing member, and a locking device disposed in each thimble-like projection of each bearing member between the inner end of said thimble-like projection and the shoulders on said arms, and said arms bridging the open inner ends of said thimble-like projections and holding the structure assembled.
6. An elastic connecting device comprising an open coiled spring, spaced bearing members at opposite ends of the spring each including a thimble-like projection entering the coil of the spring from opposite ends thereof, the inner ends of the thimble-like projections each having an annular shoulder and an aperture, arms passing through said apertures and slidable longitudinally relatively to each other, each arm having a shoulder arranged normally outside of the respective bearing member, and a locking device within each thimble-like projection of each bearing member and disposed adjacent said annular shoulder of the respective bearing member and adapted to be engaged by the shoulders on the sliding arms and causing compression of the spring whenever the sliding arms are moved longitudinally in either direction.
7. An elastic connecting device comprising an elastic element, a bearing member at each end of the elastic element, each bearing member including a thimble-like projection which enters the corresponding end of the elastic element, each thimble-like projection including an aperture at its inner end, arms passing through the apertures of the thimbles of the bearing members and slidably longitudinally relatively to each other, each arm having a shoulder, and a locking device arranged in each thimble-like projection of each bearing member for engagement by said shoulders, and whereby the structure is maintained assembled.
8. An elastic connecting device comprising spaced open-ended bearing members each including an internal annular shoulder, an elastic element carried by said bearing members, a plurality of arms mounted in said bearing members and projecting therethrough and slidable longitudinally with relation to each other, each arm having a shoulder, and a two-part locking device disposed against each internal annular shoulder for engagement by the shoulders of the respective arms whereby movement of the arms in either direction causes compression of the elastic element.
9. An elastic connecting device comprising spaced open-ended bearing members each including an internal annular shoulder, an elastic element carried by said bearing members, a plurality of arms mounted in said bearing members and projecting therethrough and slidable longitudinally with relation to each other, each arm having a shoulder, and means arranged between the shoulders of the arms and the shoulders of the bearing members to hold the parts in assembled relation and whereby movement of the arms in either direction causes compression of the elastic element.

In testimony whereof I have affixed my signature, in presence of two witnesses.

GEORGE G. HINSDALE.
